UNITED STATES PATENT OFFICE.

CARL A. FRAHM, OF CANTON, OHIO, ASSIGNOR TO CENTRAL ALLOY STEEL CORPORATION, OF CANTON, OHIO, A CORPORATION OF NEW YORK.

SHEET-OPENING METHOD.

Application filed September 13, 1923. Serial No. 662,589.

The invention relates to a method and a machine for separating metal sheets of a pack into which they have been folded and rolled in a hot mill for reducing them to a desired thickness or gauge; and the object of the improvement is to separate the sheets in such a pack by apparatus and mechanism, as distinguished from the manual means frequently employed for that purpose, and 5 to do the same without tearing or unduly wrinkling the sheets, so that they can be readily lifted apart when delivered from the machine or apparatus in a flat condition for the finishing processes. 10 The machine with which the present invention is more particularly concerned may be used in series with other apparatus for carrying out the different steps in the improved method, with which the invention 15 is more generally concerned; and when so used may be preceded in the series by a cold roll mill, sheet trimming mechanism and cold spraying means, and may be succeeded in the series by suitable delivery means including a set of flattening rolls. 20

The particular machine or mechanism however may be generally used without such other apparatus for opening sheets in a pack; and the particular method employed 25 in the improved opening mechanism per se is to progressively curve the sheet from end to end around a roll of comparatively small diameter driven in conjunction with a compressing roll of relatively large diameter, 30 whence the curved sheet is immediately flexed reversely in a straightening shoe channel substantially tangent to the smaller roll and having a sufficient width to freely guide the straightened pack without any 35 compression thereof, thereby separating or opening the sheets by reversely flexing the curved pack. 40

The improved machine, and apparatus by which the improved methods may be carried out, are illustrated in the accompanying drawings, forming part hereof, in which—

Figure 1 is a general plan view, in two sections, of the sheet opening machine, and 45 the apparatus with which it may be associated;

Fig. 2, a plan view of the sheet opening machine, with parts broken away to show interior details;

Fig. 3, a right side view of the sheet opening machine;

Fig. 4, a section of the same on line 4—4, Figs. 1 and 2; and

Fig. 5, an enlarged section of the sheet opening machine, showing the particular 60 method of opening or separating the sheets in a pack by the operation of the machine per se.

Similar numerals refer to similar parts throughout the drawings.

For carrying out a general process for opening a pack of sheets which have been rolled to an extremely thin gauge and which have been oxidized or welded together to an unusual extent, the apparatus may include in series a cold roll mill A, sheet trimming mechanism B, cold spraying means C, a sheet opening machine D, a set of straightening rolls E and a set of flattening rolls F.

When such a series is used, a pack of 75 sheets G coming from a hot mill, is first operated upon by the cold roll mill to flatten out any fullness or buckling there may be in the pack, which action may initiate a separation of contiguous sheets in particular 80 places; whence the pack may be trimmed on its edges and on each end respectively by roller and reciprocating mechanism for better preparing the pack for the opening operations; whence it may be operated upon 85 by a cold water spraying system C, which acts to successively cool the sheets from the two sides to the middle of the pack, thereby starting a separation of the sheets by the differential contraction of contiguous sheets 90 during the cooling thereof; whence it may be operated upon by the sheet opening machine D, to fully separate and open the sheets; whence it is operated upon by straightening rolls E, to straighten the 95 sheets in the pack from the curve given them by the opening operation; whence the pack may be delivered through flattening rolls F, to eliminate any waves or kinks or any fullness or buckling which may have been 100 produced therein by the sheet opening machine, and to make them ready for finishing processes.

The sheet opening machine D preferably includes two pairs of feed rolls 6 and 6' 105 driven by intermeshing gears 7 and 7' on each end by pinions 8 on a main shaft 9 having a master gear 10 on one end driven

by a pinion 11 on a shaft 12 carrying a driving pulley 13 receiving power through a belt or other source.

A pair of stationary guides 14 and 14' 5 span the space between the pairs of feed rolls, and are provided with fingers 15 extending each way into annular grooves 16 formed at spaced intervals along the rolls so as to carry the fingers well toward the 10 centers of the same, for guiding a pack of sheets from one set to the other of the feed rolls; and a similar pair of stationary guides 17 and 17' is located in rear of the 15 rear pair of feed rolls to carry the pack of sheets rearward from the same to the bending or curving rolls 18 and 19, located in rear of the feed rolls, and the upper guide 17' may be provided with fingers 17" extending rearward to the upper bending roll 20 19.

The lower bending roll 18 is of much greater diameter than the upper bending roll 19, and as shown in the drawings, the ratio of these diameters may be as seven to one 25 and one-half. These rolls are driven in unison by intermeshing gears 20 and 21 on their ends by means of driving gears 22 on each end of the larger roll, and intermediate gears 23 between gears 22 and the lower 30 gears 7' on the lower rear feed roll.

The smaller roll 19 may be supported and held in position by backing or bearing blocks 24, which may be made of wood or other suitable material for preventing a 35 grinding of a feed roll; and these backing blocks may be secured in position by means of an angle bracket 25, upon the rear side of which is secured an upright shoe plate 26 having its rear face 27 extending directly 40 upward from and substantially tangent to the rear side of the smaller bending roll 19, the lower end of which shoe plate may be cut to conform to the periphery of the smaller bending roll and may act as a 45 scraper to clean the same.

An abutment shoe 28 is located in rear of the bending roll 19 and the shoe plate 26, and is preferably provided with fingers 28' extending downward into annular 50 grooves 29 formed at spaced intervals along the lower bending roll 18. The forward face of the abutment shoe 28 is spaced in rear of the rear face of the shoe plate 26, and is substantially parallel therewith, so as to 55 form a straight-way or shoe-channel 30 extending upward from the rear side of the bending roll 19, and being wide enough to freely pass the sheets of a pack upward without any compression, after they have 60 been separated or opened in the lower part of the channel.

A set of straightening rolls E, located above the outlet of the shoe channel 30, may include a pair of spaced driven rolls 31 and 65 31' having alternate ends driven by chain

gears 32 and 32' from the main shaft 9, and an idle roll 33 located in rear of the interval between the driven rolls, so as to form ways 34 between the peripheries of the rolls which will reversely bend the opened sheets by a 70 compressing action.

A series of guide fingers 35 are preferably counter-sunk into the rear face of the shoe plate 26 and extend thence upward through annular grooves 36 formed at intervals in 75 the peripheries of the driven rolls 31 and 31', between which they are reversely curved upon the center of the idle rolls 33; and a series of guide bars 35' preferably rise from the abutment shoe 28, in rear of the guide 80 fingers 35, so as to form a guide way for the upward movement of the sheets of a pack as they rise from the opening mechanism.

A pair of guides 37 and 37' is preferably 85 mounted above the straightening rolls E, to form a curved way 38 for carrying the sheets upward and rearward to a pair of feed-out rolls 39, which deliver the pack of open sheets upon a table 40 and into the flattening 90 rolls F, whence the opened sheets may be discharged on to a conveyor table 41.

Suitable means are provided for adjusting the several sets of rolls and guides, which may include screws 42 for the feed rolls, 95 screws 43 for the feed guides, screws 44 for the larger curving roll, screws 45 for the abutment shoe, screws 46 for the idle straight rolls, screws 47 for the delivery guides, and screws 48 for the feed-out rolls; and the 100 several operating parts are adjusted for performing their several functions in the work to be performed by them, as follows:

In the operation of the opening machine, a pack of sheets G is fed by the feed rolls 105 6 and 6' through the guides 14, 14' and 17, 17' so as to enter the lower forward nip of the bending rolls 18 and 19; the feed rolls being adjusted to drive the pack forward for the curving operations, and the guides being 110 adjusted to hold the pack stiff and straight as it approaches the curving rolls.

Upon entering the nip of the curving rolls the pack is progressively and continuously curved sharply upward by bending around 115 the periphery of the smaller curving roll 19 as it is acted upon by the larger curving roll 18, which is adjusted to compress the pack during the curving operation, whence the curved sheet is directed upward into the 120 shoe channel 30.

Upon emerging from the curving rolls, the curve which has been given to the pack tends to cause it to continue rearward over the smaller curving roll, but as soon as the 125 pack impinges the rear face of the shoe plate 26 it is flexed directly upward, as shown at 49 in Fig. 5. By reason of the abutment given to the curved pack by the rear face of the shoe 28, as shown at 50 in 130

Fig. 5, the flexing of the curved pack tends to straighten out the curve or bend of the same; and as this flexing action occurs freely without any compression of the comparatively wide shoe channel 30, the sheets are separated and opened by the differential movement of contiguous sheets after the bond or adhesion has been broken by the compressing action of the curving rolls.

10 As the pack is fed through the machine, the opened sheets continue upward between the straightening rolls E, which reversely curves the pack by a compressing action, and sets the sheets straight from the curve which has been given them by the opening operation; after which the sheets of the opened pack are driven through the guide-way 38 to the feed-out rolls 39, and thence on through the flattening rolls F onto the delivery conveyor 41.

By these means, preceded if need be, by either one or more of the cold rolling, the sheet trimming or the spray cooling operations, a pack of sheets of the thinnest gauge and greatest adhesion can be so completely separated and opened, that they may be readily lifted apart when delivered from the machine, without any rupture or tearing of the same, and in proper trimmed, straightened and flattened condition for the finishing processes.

I claim:

1. The method of opening a pack of sheets which consists in continuously and progressively curving the pack under compression in one direction, and then flexing the pack without compression in reverse directions.

2. The method of opening a pack of sheets which consists in cold rolling the pack, then continuously and progressively curving the pack under compression in one direction, and then reversely flexing the pack without compression progressively from end to end.

3. The method of opening a hot pack of sheets which consists in trimming the pack, then continuously and progressively curving the pack under compression in one direction, and then reversely flexing the pack without compression progressively from end to end.

4. The method of opening a hot pack of sheets which consists in spray cooling the same, then continuously and progressively curving the pack under compression in one direction, and then reversely flexing the pack without compression progressively from end to end.

5. The method of opening a pack of sheets which consists in continuously and progressively curving the pack under compression in one direction, then reversely flexing the pack without compression progressively from end to end to open the sheets, then reversely curving the pack to straighten the sheets, and then collectively flattening the sheets.

6. The method of opening a pack of sheets which consists in cold rolling the pack, then trimming the pack, then spray cooling the pack, then curving and reversely flexing the pack progressively from end to end to open the sheets, then reversely curving the pack to straighten the curved sheets, and then collectively flattening the opened sheets.

CARL A. FRAHM.
